UNITED STATES PATENT OFFICE.

JOHN GOOD, OF BROOKLYN, NEW YORK, ASSIGNOR TO GOOD INVENTIONS CO., OF NEW YORK, N. Y., A CORPORATION OF NEW YORK.

INCLOSED LIQUID-FUEL BURNER.

Application filed May 1, 1918, Serial No. 231,910. Renewed September 26, 1925.

The invention relates to the organization of the elements of burners and especially those which are ignited by an electric spark, the purpose being to enlarge the permissible range of structural and adjustment variations of the various elements. It is directed especially toward maintaining the fuel in liquid form up to the point of delivery into the combustion space, a certain disposition of the igniting spark plug which tends to keep the plug body clean and free of soot and fuel, and a certain special disposition of the spark plug terminals with respect to the mixture which tends toward certainty of ignition under different conditions.

The accompanying drawing illustrates the invention in both of its features combined in an inclosed liquid fuel burner, the figure being a central longitudinal section.

20 The said burner is not materially different in function from that shown in my co-pending application Serial No. 195,506 filed October 9, 1917. A flow of air from a fan or other air source enters the burner casing 1 from a pipe 2 and part of it passes through a jet hole or nozzle 3 in the end of the shell 4 while the remainder passes into the annular space between shell and casing from which it enters to the interior of the shell through 30 the zone of fine holes 5. The air from the nozzle 3 atomizes liquid fuel from the nozzle 6 connecting with the liquid fuel in a receptacle 7 and thereby projects a liquid spray into and through the shell 4. The receptacle 7 is subject to a pressure difference as 35 by the pressure connection 8 to the air pipe 2, which is desirable if the receptacle is far below the nozzle orifice or if a high combustion rate is desired with low air pressures. 40 The air jet hole 3 may be and preferably is in aspirating relation to the liquid orifice, but depending on the pressure imparted to the liquid fuel in receptacle 7 this may be varied as circumstances may dictate. When 45 the burner is intended for continuous operation such a pressure pipe is desirably provided with a small adjustable vent-hole 9 to prevent an accumulation of pressure in the receptacle. The atomized liquid spray is 50 ignited, prior to its mixture with the inward flow of combustion-supporting air from the holes 5, and for this reason the electrodes 10 and 11 of the double-electrode spark plug are mounted so as to bring the spark gap at 55 about the point indicated, that is to say, close

to the spray source and intercepting the spray therefrom. The resulting flame receives more air through the air holes in the flange of the shell and passes from the ignition chamber within the shell into the flame tube or other enclosed space to be heated, escaping from the latter to an outlet open to atmosphere but not shown. The air flow to the ignition and mixing chamber may be produced by any suitable means independent of the flame establishing a difference of pressure between the outlet to the flame passage and the pipe 2.

60 The electrodes 10 and 11 are carried respectively by the metallic shell 13 and the insulating core 14 of the spark plug. This latter is screwed into the end of a tubular neck 15 projecting from the shell 4, the electrodes being of such length as to extend through the interior cavity within this neck to the 70 position desired for the spark gap in the interior of the ignition chamber. Except for the length of the electrodes, the plug may be of ordinary, properly insulated construction having an annular cavity 16 within its shell 13 as usual. The cavity represented by the interior of the neck 15 forms an extension of the spark plug cavity and is located preferably in the upper side of the shell of the ignition chamber and as close to 75 the spray source as possible without however being directly in line with the fuel nozzle so that a liquid jet from the latter would enter it and wet the interior of the plug.

80 The entrance to the neck cavity is also outside of the lateral boundaries of the spray cone from the spraying means indicated by the dotted lines so that the spray cannot directly enter into it, but the spark-gap is nevertheless directly in the path of the liquid spray as above stated. Otherwise the neck construction of the ignition chamber may be of various shapes and may or may not be integral with the shell as preferred. The object is to obtain a cavity or dead end 85 pocket of considerable depth surrounding the electrodes of the spark plug. The said cavity is, by preference, inclined toward the air pipe 2 which position is preferred because it brings the entrance to the cavity 90 substantially parallel to the side of the spray cone and improves and reduces the external contour of the apparatus as a whole, while at the same time permitting a maximum length of cavity. The terminal of the 105 110

- grounded electrode 10 is shown in the drawing as bent transversely to form the spark-gap, this being desirable in that it tends to drain impinging liquid away and to keep it from bridging the gap and thereby a more moderate sparking current is rendered possible of use but this formation is not essential with an adequate sparking current and especially when the electrodes are mounted 5 in an inclined cavity as shown in the drawing because the very considerable force of spray tends to produce the same effect by blowing the liquid away from the gap and preventing it from collecting thereon. The 10 fuel nozzle 6 is permanently fastened to the outer shell of casing 1 and between the two shells it is constituted of a relatively slender tube which is directly exposed to and crosses the air passage which leads the combustion-supporting air to the ignition and mixing chamber. It is thereby cooled, the heat conducted to it through its metallic surroundings being dissipated to the air current at a sufficient rate to avoid the possibility of vaporization of the liquid within the nozzle. Inasmuch as the capacity of the bore of the fuel nozzle is determined with reference to the air flow, the vaporization of even a part 15 of the liquid in the nozzle and the corresponding change of volume resulting from such vaporization, operates to change the proportions of fuel and air to such extent as to interrupt combustion or forestall ignition when the burner is still hot from a previous 20 operation. By providing for the air cooling of the liquid nozzle and by making it slender shape or of small mass, near its orifice, as above explained, these possibilities of mal-functioning are effectually eliminated 25 and by the disposition of the electrodes in a cavity the entrance to which is normally 30 outside of the spray cone a very high degree of reliability is attained. The part of the fuel nozzle exposed to the air is shown as provided with heat-radiating ribs 17 which 35 are merely for facilitating the dissipation of its heat. Certain features of the structure of the burner above disclosed and not herein claimed form the subject of my prior application above referred to and certain other 40 applications.
- I claim:
1. In apparatus for burning liquid fuel, an inner shell constituting a fuel-mixing and flame chamber and having an outlet for the flame and combustion products, an outer burner casing providing a passage for air to said chamber and having an air entrance remote from the heat of the combustion, a liquid fuel supply chamber, a nozzle tube 45 adapted to conduct the liquid fuel therein to said chamber, said tube being provided with a heat-dissipating rib means exposed to the air flowing in the space between said outer casing and inner chamber and being thereby 50 maintained at a relatively low temperature.
  2. A burner for liquid fuel having an ignition and mixing chamber, means for admitting combustion air into said chamber, a fuel spray nozzle opening into said chamber, and an electric igniter for igniting the mixture within the chamber, said igniter being set in a cavity which is in the upper portion of the burner and is inclined away 55 from the source of spray and the entrance to which is outside the zone of the spray from said nozzle, the igniting portion of said igniter extending from the cavity to a point within the zone of the spray.

In testimony whereof, I have signed this 60 specification.

JOHN GOOD.
